UNITED STATES PATENT OFFICE.

ROBERT CREUZBAUR, OF BROOKLYN, E. D., NEW YORK.

TIDE-WATER ELEVATOR.

SPECIFICATION forming part of Letters Patent No. 241,937, dated May 24, 1881.

Application filed June 25, 1880. (No model.)

To all whom it may concern:

Be it known that I, ROBERT CREUZBAUR, of the city of Brooklyn, E. D., in the county of Kings and State of New York, have invented 5 a new and useful combination of mechanism for raising water by the force of the tide, named the "Tide-Water Elevator," which is fully described in the following specification, reference being had to the accompanying drawings.

10 The principal object of my invention is to raise water on and near tide-water coasts, bays, inlets, and rivers, to be applied to cleansing house-closets and drains, to the flushing of sewers, for sprinkling streets, and for manufacturing and other purposes. I accomplish the 15 object by causing the flood-tide to store water in a reservoir, this stored water being prevented from returning with the ebb-tide by a self-closing valve. When a sufficient head or 20 difference of level is established between the stored water and the ebb-tide a channel is opened, which admits the stored water to a hydraulic ram or other water-elevating mechanism, which delivers the water where desired.

25 In the accompanying drawings, Figure 1 is a sectional elevation of my tide-water elevator, and Fig. 2 is a sectional elevation of a modification of a portion of the same.

30 In Fig. 1, A is a pipe or drain through which the tide-water flows into the large reservoir B, the pressure of the incoming water forcing open the valve C, which may be made so as to be very little heavier than water, being made hollow, or loaded with cork, or made of light material, 35 so that the water in the reservoir B will attain nearly as high a level as the tide. When the tide recedes the valve C closes and prevents the escape of the water from the tank B.

35 D is a large pipe or a small tank, in which 40 the tide rises and falls freely through the branch pipe d', connecting with pipe A. This pipe or tank D may be inside of the reservoir B, as shown, or it may be outside and separate from it. In this pipe D a float, F, operates, 45 attached to rod E, which rod is attached to centrally-pivoted lever G, the other end of lever G being attached to valve H, which controls the entrance into drive-pipe I, which feeds the hydraulic ram R. The water raised by the 50 ram R passes through the pipe K to its destination. The float F may be vertically adjustable upon rod E by nuts n n.

Fig. 1 shows the ram R inoperative, the valve H being closed by the float F through its tendency to rise with the water entering tank D. 55 During ebb-tide the valve C remains closed, and as soon as the tide has sufficiently receded the weight of float F, when no longer sustained by the water, overcomes the weight of valve H with its attachments, as well as the pressure 60 of the water upon the same. As soon as valve H is partly open the water-pressure upon the same is sufficiently balanced to cause the float F to descend suddenly and sufficiently to throw valve H wide open, thus setting the ram into 65 instant operation. The float F need not be a body or vessel lighter than water and able to float upon the same, but may be simply a displacer of water, as a piece of wood, iron, or of any other substance, a corresponding displacer, 70 G', being attached to the outlet-valve H of such relative weight that when both bodies F and G' are submerged the valve H, with its displacer G' and attachments, will be heavy enough to seat. When the water has receded 75 from displacer or float F, leaving it dry, a weight equal to the body of water displaced by F and its attachments will be acting in overcoming the overweight of valve H and its displacer G' and attachments, as well as the pressure of 80 the water upon the valve H. For instance, the valve having an area of twenty square inches and the depth of water upon it being twenty-eight inches, the water displaced by float or displacer F must be over twenty pounds, 85 added to the weight necessary to overcome the overweight of valve H and its attachments.

The reservoir B is best made large enough, so that its water-level will not fall very much during the operation of the ram in order to 90 prolong its operation under a good head.

Instead of the float F and lever G, or of two displacers, G' and F, and rock-beam G, with their attachments, the arrangement shown in 95 Fig. 2 may be used.

The small tank D adjoins the reservoir B, with a flat partition, d², between the two, into which a flexible diaphragm, M, is inserted at a proper height, and centrally pivoted by rod m' to the upright arm h' of valve H. While the water stands equally high in tanks B and D, this diaphragm M stands centrally and the valve H is closed. When the water has receded sufficiently from tank D to uncover the diaphragm 100

more or less on that side, the pressure of the water in reservoir B will force the diaphragm into the position shown, thus opening valve H. As the pressure of the water upon valve H before its opening will give a greater resistance than when through its opening that pressure is no longer unbalanced, the diaphragm M, upon the opening of the valve H, will suddenly move farther in toward tank D, thus throwing valve H wide open. When the diaphragm M becomes sufficiently uncovered on the reservoir B side also, the diaphragm returns to its central position, aided by the weight of valve H.

The inlet into pipe I should be protected by a large strainer, N, Fig. 1, to prevent the entrance of obstructions into the ram.

The float F, instead of being in a pipe or tank, D, may be anywhere in unobstructed tide-water.

The details can be varied according to circumstances and in many ways.

I do not claim in an artificial spring or bulk-head an underground drain combined with a hydraulic ram and a drive-pipe which receives water from a reservoir suitably located in the drain, the waste water of the ram and of the reservoir being discharged into a continuation of the drain which extends past the ram; but

What I claim as my invention is—

1. The combination, with a reservoir and a valve or gate through which it is supplied with water by flood-tide, but which is closed during ebb-tide, of a hydraulic ram and drive-pipe adapted to receive water from said reservoir and to deliver it in elevated positions, substantially as herein described.

2. The combination, with a reservoir and a valve or gate through which it is supplied with water by flood-tide, but which is closed during ebb-tide, of a hydraulic ram adapted to deliver water at elevated positions, a drive-pipe for feeding said ram from said reservoir, and a valve which admits water from said reservoir to said pipe, and which is automatically controlled and periodically closed and opened by mechanism operated by the rising and falling of the tide, substantially as herein described.

3. The combination of storage-basin B with inlet A, valve C, auxiliary tank D, displacers G' and F, rock-beam G, channel I, and water-raising mechanism R, with their connections and appurtenances, operating conjointly substantially as described.

ROBERT CREUZBAUR.
